UNITED STATES PATENT OFFICE.

CHARLES OWENS, OF CHATTANOOGA, TENNESSEE.

INTERNAL-COMBUSTION ENGINE.

1,264,968.

Specification of Letters Patent.

Patented May 7, 1918.

Application filed January 15, 1916, Serial No. 72,279. Renewed December 3, 1917. Serial No. 205,234.

To all whom it may concern:

Be it known that I, CHARLES OWENS, a citizen of the United States, residing at Chattanooga, Tennessee, have invented certain new and useful Improvements in Internal-Combustion Engines, of which the following is a specification.

My present invention relates to improved internal combustion engines and to the method of operating the same, and has among its objects to increase the efficiency of the engine and decrease the consumption of fuel.

The invention includes the novel structural arrangement and method of operation hereinafter more particularly described and defined in the appended claim.

An embodiment of my invention is illustrated in the accompanying drawing, in which—

Figure 1 represents in side elevation (partly broken away) a multiple cylinder engine of the type usually embodied in automobile construction.

Fig. 2 is an enlarged detail view.

Referring by reference characters to this drawing, A designates the radiator of the engine which is indicated by letter B.

The exhaust manifold is lettered C and the carbureter D. E indicates a needle valve which controls a passage leading into the manifold F, with which passage connects a pipe G of small diameter for the supply of aqueous liquid.

The needle valve E is preferably arranged so as to be controlled from the dash board J when used in connection with automobile engines by rod H, and the needle valve d of the carbureter may likewise be arranged to be controlled by rod I.

The stem of the needle valve of the carbureter is provided with an arm d', which in turn is connected by a link d'' with an arm k connected to the pivot pin k' of a butterfly valve k'' located in the air intake passage k leading to the carbureter.

The intake end of pipe G connects with a source of water supply, to wit, the water space of the radiator, and I preferably extend said end g down into the pipe or connection a which discharges the heated water from the water jacket of the engine to the upper part or tank of the radiator, this arrangement dispensing with the necessity of a strainer.

From this point of connection to the radiator, the pipe G passes to the rear of the

engine and enters the exhaust manifold C, when it connects with or merges into a pipe G' which passes longitudinally through said manifold to the front end, whence it issues at the point indicated at g' and extends to or connects with the fuel intake at the needle valve connection E by pipe extension or connection G².

It will be understood that the pipe portions lettered G, G' and G² may be made as separate pipes connected together by suitable couplings, or may be made as one continuous pipe as desired.

This tube G, G', G², or at least portion G' which passes through the exhaust manifold, is of larger diameter and made of copper or some similar material which is a good heat conductor.

By having such a pipe passing through the exhaust manifold in the manner described, it is subjected to the intense heat of the products of combustion as they issue directly from the exhaust ports.

It thus constitutes a flash steam generator and superheater or still, and the steam is superheated to such a degree that on entering the intake filled with vaporized gasolene, it is decomposed into its constituent elements of hydrogen and oxygen, and combines with the hydrocarbons of the mixture from the carbureter to form practically a water gas.

The precise method of operating an engine or motor equipped as above described is as follows:—

The motor is started with a gasolene mixture normally used to run the motor. As soon as the motor has run a minute or two, or long enough to get the exhaust pipe C hot, the handle H of the needle valve E is given a slight turn sufficient to open the valve. As soon as this is opened the pipe G—G'—G² is unobstructed throughout its entire extent and the suction of the engine in drawing the mixture from the manifold F into the cylinders of the motor, is sufficient to draw water from the radiator A through the pipe portion G into the portion G'. As soon as the water strikes the pipe G' it is immediately converted into steam, the water continuing to flow through the pipe G into the pipe G' until the steam pressure is equal to or greater than the vacuum pressure caused by the suction action of the pistons of the engine, at which time the water will be automatically cut off by the occupation of the vacuum by the steam,

- The suction from the pistons of the motor in drawing the mixture from the manifold immediately begins to draw in the hot steam or vapor along with the gasoline mixture.
- 5 As soon as this occurs it becomes necessary to close down on the needle valve of the carburetor D in order to reduce the gasoline mixture, this at the same time causing the supply of air to be reduced by the connections to the butterfly valve already described.
- 10 The result is an increased power from the motor.

As soon as the suction action of the pistons has drawn enough of the steam from the tube G' to begin to cause a partial vacuum in the tube G', water again is drawn from the radiator A through the pipe G into the hot pipe G' in the exhaust pipe C, and the water coming in contact with the hot tube G' is again converted into steam and all water remaining in the pipe G is again returned by the steam into the radiator A as soon as the steam pressure in the pipe G' exceeds the vacuum pressure of the pistons. The steam which passes from the pipe G' into the radiator A is condensed, owing to the fact that it passes into the water.

Two things are very noticeable with this system:

- 15 The diminished quantity of gasoline required and the small opening that is necessary to give the throttle. Continued tests have demonstrated a very material increase in efficiency, and power.
- 20 It is very apparent in the operation of the motor that it runs best when barely enough gasoline is permitted to go in to insure combustion.

A chemical analysis of my improved mixture, including the superheated steam and the ordinary mixture of air and gasoline, shows the following:

Table #1. Improved mixture.

45	Carbon dioxid	12%
	Oxygen	20.40%
	Carbon monoxid	.36%
	Hydrogen	24%
50	Hydrocarbons as propane	.71%
	Nitrogen	78.17%

Table #2. Ordinary mixture.

55	Carbon dioxid	.36%
	Oxygen	19.74%
	Carbon monoxid	None.
	Hydrogen	None.
	Hydrocarbons as propane	2.9%
	Nitrogen	77.00%

- 60 A comparison of these tables shows that

my improved mixture, while containing a lower percentage of hydrocarbons as propane (which is a combustible of low caloric value) on the other hand contains carbon monoxid and hydrogen (both absent from the ordinary mixture), which are combustibles of very high caloric value, and, therefore, my improved mixture, while requiring less gasoline, gives greater power by reason of the greater caloric value of the hydrogen and carbon monoxid.

While I have referred above to opening the needle valve E as soon as the engine gets heated up, it will be understood that this need not be necessarily wide open, as under certain conditions it may be desirable to vary the area of the passage leading to the inlet manifold to provide local control for the passage of steam. This in no way alters the fact that the passage of steam to the intake and engine cylinders is governed solely by the vacuum pressure produced by the pistons through the pipe being open throughout its entire length to simply enable the variation in the amount of steam drawn in by said vacuum pressure to be varied at will to suit conditions.

I claim as my invention:

In combination with an internal combustion engine and a water supply means for automatically generating and supplying a combustible mixture to the fuel intake of the engine, a pipe having one end directed downwardly into the water of the system and its other end communicating directly with the fuel intake between the carburetor, and the engine, said pipe being normally open and unobstructed throughout its entire extent and having a portion passing through the path of the exhaust gases to be acted on by direct contact therewith, and of dimensions to constitute a flash steam generator and superheater, said unobstructed pipe permitting it to be normally filled with superheated steam at substantially the same pressure as that caused by the suction action of the pistons, which steam is withdrawn and replaced by steam generated by additional water, the supply of said additional water being governed solely by the suction created by the suction stroke of the piston, and the degree of applied heat from the exhaust of the engine.

In testimony whereof, I affix my signature in presence of two witnesses.

CHARLES OWENS.
